Primary Examiner — Mark T. Philipps*(74) Attorney, Agent, or Firm* — BKRP LLC(57) **CLAIM**

The ornamental design for a cutting tool as shown and described.

DESCRIPTION

FIG. 1 is a perspective view of an embodiment of the design implemented on a drill bit;

FIG. 2 is a top view of the design of FIG. 1;

FIG. 3 is a perspective view of an embodiment of the design implemented on a drill bit;

FIG. 4 is a top view of the design of FIG. 3;

FIG. 5 is a perspective view of an embodiment of the design implemented on a drill bit; and,

FIG. 6 is a top view of the design of FIG. 5.

The broken lines comprised of short dashes represent portions of the cutting tool that form no part of the claimed design.

The alternating long and short dashed broken lines define the bounds of the claimed design and form no part thereof.
